TOY VEHICLE

Heinrich Müller, Nuremberg, Germany

Application March 24, 1938, Serial No. 197,760
In Germany December 6, 1937

20 Claims. (Cl. 46—210)

The present invention relates to toy vehicles and is particularly directed to an improvement in toy vehicles of the type in which the steering of the vehicle is effected by the operator from a distance.

Toy vehicles provided with means for steering or controlling their movements from a distance have already been known for some time. In known devices of this kind the steering of the 10 toy has been effected by a flexible transmitting means consisting of a double shaft, whereby one of the shafts acts as a driving means while the other one serves as a controlling and steering means for the toy. I have found, however, that 15 an arrangement like that is not satisfactory, particularly because the concentrically arranged shafts considerably interfere with the free and easy operation of the toy.

I, therefore, provide the toy with electrical or 20 mechanical propelling means and use a flexible shaft, or one provided with joints, solely for the steering of the vehicle. In this way I provide a toy that for its operation from a distance requires only one single flexible shaft, which, since 25 it has to perform only one function now, can be thinner and more flexible and just sufficiently rigid to operate with ease and perfect satisfaction even the lightest and smallest toy vehicle.

One principal advantage of my invention is the 30 fact that effectiveness of the steering means on reversals in the direction of the toy is considerably increased through use of either a smooth wire or a spiral with space between the individual coils. The wire as well as the spiral possess great 35 torsional rigidity, for which reason motion occurring at one end of the transmitting means is passed on without back-lash to the other end of the spiral or wire.

Another advantage resulting from the use of a 40 spiral or wire is, of course, the increased flexibility and suppleness of the shaft, as well as the fact that the latter is lighter in weight and therefore cheaper in price if the length is the same.

If a wire spiral with space between the individual coils be used, it will be almost impossible 45 for a child to stretch the spiral, and if the latter be so constructed that the space or distance between the coils is somewhat smaller than the diameter of the wire used in making the spiral, disturbing entanglements of the spiral will be out of the question.

Particularly suited for the purpose in question is a wire spiral in which the outer diameter of the coils is approximately four times as large as

the diameter of the wire used in the construction of the spiral.

The flexible shaft, when serving as a means for turning and operating the steering shaft connected to the steering wheel, or pair of steering wheels, will be particularly efficient in its capacity as a steering and controlling means for the movements of the vehicle, when between the flexible shaft and the steering shaft suitable means are interposed which are adapted to transmit movement from the flexible shaft to the steering shaft of the steering wheels at a reduced ratio. It will be apparent that, when such means are provided, the swinging of the steering elements into either of their extreme positions will require a plurality of turns of the flexible shaft, and that, because of this fact, it will not only be possible then to turn the steering wheels into their extreme positions but also into any intermediate positions within the range of an existing steering radius. The steering possibilities are thus vastly increased, and the toy can be steered in any desired direction and to any predetermined place. The vehicle may be made to run in a straight line direction and back again to its starting point, or turn on the spot and run through curves or in circles.

As already mentioned, the flexible shaft has to turn several times in order to swing the steering wheels into their extreme positions. That is 30 why the torsional stress actually caused through transmission of the steering force is comparatively very small, so that thin and flexible wires (for example: a thin and flexible copper wire) can be used for the purpose.

The use of a wire like that has the additional advantage that it can easily be straightened out by the child when it has lost its shape through bending or winding around an object.

With a thin and flexible wire used as a flexible 40 shaft it is possible to steer even the smallest vehicles with perfect satisfaction and precision. Such wire, moreover, has the further advantage that it is practically invisible to the eye, thus adding to the attraction of the game and making 45 the performance appear like witchcraft.

The term "flexible shaft" as used in the present application does not limit the invention to merely the use of a spiral or ordinary wire, or a shaft consisting of several portions joined together with the aid of coupling means, but comprises all flexible means, articles or constructions (as for instance: rubber cords) possessing a sufficient amount of torsional rigidity to transmit over a certain distance turning motion in either clock- 50

wise or counter-clockwise direction to the steering elements of a toy receiving its propelling force from a clock-work or electrical device mounted inside said toy.

5 The flexible shaft used as a means for transmitting steering motion to a toy vehicle may be fastened to the vehicle in various ways. It is preferable, however, to connect it to the toy in such a way that the free end of the shaft leaves the toy body at the top.

10 If the flexible shaft be fastened to the toy in such manner that it leaves the top of the toy body in vertical or substantially vertical direction the steering of the toy will be considerably facilitated, since turning of the shaft will then have a full and unobstructed effect on the steering means of the vehicle.

15 If fastened to the toy in the aforementioned way the flexible shaft can also be used as a handle for lifting the vehicle from the running surface without upsetting its horizontal or substantially horizontal position with respect to that running surface.

20 Another advantage of connecting the flexible shaft to the top of the toy is the fact that the vehicle is thereby enabled to run through circles and turn on the spot underneath the arch-like curvature of the flexible shaft lying on the running surface with a portion of its length without 25 coming in troublesome contact with the latter.

25 The present invention is a means for controlling and steering the movements of toy vehicles of any kind and construction, whereby it is unimportant whether the flexible shaft is used for steering merely one wheel or two wheels, as is necessary in cases where the toy has been given the shape of an automobile.

30 With the foregoing and other objects in view I will now proceed to describe my invention with 35 the aid of the accompanying drawings showing a preferred embodiment of the invention. But it is to be understood that changes, variations and modifications which come within the scope of the claims hereunto appended can be resorted 40 to.

45 In the drawings:

Fig. 1 is a side elevation of a toy-vehicle with certain parts broken away to illustrate the working parts by means of which turning movement 50 occurring at the flexible shaft is passed on to the steering shaft of the steering wheel at a reduced ratio;

Fig. 2 is a bottom plan view of the toy;

Fig. 3 is a fragmentary plan view of the under- 55 side of the vehicle;

Fig. 4 is a plan view of one form of construction of a mechanism for rotating the flexible shaft, provided with hand wheel and working parts for transmitting turning movement at an 60 increased ratio;

Fig. 5 is a fragmentary view of a wire, serving as flexible shaft, provided with a handle for turning the wire;

Fig. 6 is a fragmentary elevational view of a 65 vehicle showing the flexible shaft directly connected to the steering shaft of the steering wheel;

Fig. 7 is a detail view, showing how the flexible shaft may be connected to the steering shaft of the steering wheel;

70 Fig. 8 is a diagrammatical view on a reduced scale of a toy vehicle provided with a flexible steering shaft in the form of a spiral, which enables the vehicle to run through circles and curves underneath the arch-like curvature of the 75 shaft;

Fig. 9 is a fragmentary view on a considerably enlarged scale of a spiral spring serving as flexible shaft, showing that the distance between the individual coils is smaller than the diameter of the wire of which the spiral is made;

Fig. 10 is a fragmentary view of a flexible shaft consisting of a plurality of portions joined together by means of elastic coupling sleeves;

Fig. 11 is a plan view of the bottom plate, seen from above, of a vehicle, the front wheels of 10 which are coupled to steering arms which jointly and uniformly are moved toward the right or left by the steering movement of the flexible shaft;

Fig. 12 is a diagrammatical view of the toy on a reduced scale, showing how the flexible 15 shaft is fastened inside the vehicle;

Fig. 13 is an elevational view of a simple mechanism for turning the flexible shaft. Parts of the hand wheel have been broken away to show the toothed on the inner side of the wheel. 20

25 In these drawings I have illustrated one embodiment of my invention and, for the purpose of this illustration, have shown the invention as applied to a toy, the body 1 of which is formed in imitation of an automobile. Mounted in the rear portion of the automobile is a clock-work 2 adapted to be wound up by means of the stem 3. The clock-work 2 drives the axle of the propelling wheels 4. Arranged in front of the clock-work 2 is a bearing frame 5 in which is journaled a vertical shaft 6. Fastened to the shaft 6 is a bearing frame 7 in which is rotatably journaled the axle 8 of the steering wheel 9. It is obvious, therefore, that the steering wheel 9 can be swung to the left or right by the shaft 6. The steering wheel 9, projecting downwardly through an opening in the bottom plate 11 of the toy body 1, rolls on the running surface 12. The running and steering wheel 9 serves as front support for the toy body 1, while the front wheels 13 are not in contact with the running surface 12 and for that reason do not roll on the latter, and hence, turning of the steering wheel 9 by means of the shaft 6 will effect the steering of the toy.

30 The shaft 6 of the running and steering wheel 45 9 carries at its upper end a gear 14, to which is connected a direction indicator or pointer 15. This pointer 15 projects beyond the casing of the toy body and thus can be watched by the operator of the toy. It indicates the position of the 50 running and steering wheel 9. Gear 14, mounted on the shaft 6, is provided in its forward portion (see Fig. 2) with a recess 16 in which engages a stop member 17, limiting the rotation of gear 14 and shaft 6 of the steering wheel 9 in clockwise 55 as well as counter-clockwise direction.

Attached to bearing frame 5 is another bearing frame 18 in which is journaled a shaft 19, carrying a gear 20 and a pinion 21. Pinion 21 meshes with gear 14, while gear 20 meshes with a pinion 22. Pinion 22 is mounted on the steering shaft 23. The latter is journaled in a frame 24 and is secured in that frame against axial displacement by means of an adjustable collar 25. In the embodiment shown in the drawings frame 24 has been mounted on the clock-work 2. The steering shaft 23 projects upwardly through an opening 26 in the casing of the toy body 1. Fastened to the steering shaft 23 is the flexible shaft 27, 70 as which in the embodiment illustrated in the drawings a spiral has been used. Attached to the upper end of the spiral is a handle 28, which serves to impart turning movement to the spiral. In the illustration the width of the spiral has 75

been considerably enlarged, the diameter of the spiral being actually very much smaller.

When the handle 28 is turned in clockwise or counter-clockwise direction the spiral 27 turns in the same direction and thus rotates the steering or controlling shaft 23, which via pinion 22, gear 20, pinion 19 and gear 14 causes a rotation of the vertical shaft 6 and thereby effects a turning to the right or left of the running and steering wheel 9.

Instead of using a simple handle as 28 it is also possible to arrange at the actuating end of the flexible shaft 27 a steering mechanism 29 as illustrated in Fig. 4. Rotatably journaled in the 15 casing of this steering mechanism is a shaft 30. It carries at its upper end a steering wheel 31 and at its lower end a gear 32. Gear 32 meshes with a pinion 33 which latter is mounted on a shaft 34. Mounted on the same shaft is a crown-wheel 35. This crown-wheel rotates a pinion 36 mounted on a shaft 37, which latter is journaled in the casing 29 and imparts rotary movement via the flexible coupling sleeve 38 to the flexible shaft 27.

It is also possible to devise the steering mechanism as illustrated in Fig. 13. This latter steering mechanism provides a bearing 49 consisting either of a solid piece of metal or of a casing similar to the one shown in Fig. 4. In metal piece 49 is journaled a shaft 30 for a hand-wheel 31. Shaft 30 is held in position by riveted joint 50. Hand wheel 31 is provided on its inner side with a toothed which meshes with a pinion 52. The pinion 52 is mounted on the driving shaft 37 which likewise is journaled in bearing 49. The driving shaft 37 is fastened to the flexible shaft 27 by means of the coupling sleeve 38. The result produced by this steering mechanism is the same as that produced by the steering mechanism 40 29 illustrated in Fig. 4.

A flexible coupling sleeve may also be used for connecting the flexible shaft 27 to the steering shaft 23 or the vertical shaft 6. A connection like that is illustrated in Fig. 7.

It is further possible to use as flexible shaft, instead of the spiral 27, a flexible metal wire 40 possessing a sufficient amount of torsional rigidity. See Fig. 5.

In the form of construction shown in Fig. 12 50 the thin metal wire 40 has been fastened to the steering and controlling shaft 23 by means of the coupling sleeve 39 inside the body of the vehicle. If connected that way the wire is practically invisible and the performance of the vehicle looks like witchcraft to the spectator.

If a spiral 27 be employed as flexible shaft it is advisable to use a spiral in which the space or distance a between the coils is smaller than the diameter d of the wire of which the coil is made.

60 A spiral like that is shown in Fig. 9 on an enlarged scale. This prevents disturbing entanglements of the coils of the spiral 27.

Experience has shown that spirals the outer diameter of which is approximately four times 65 that of the wire used in their construction are most suitable for the purpose in question.

The flexible shaft 27, 40 and its arrangement and use make it a suitable means for steering a toy and for controlling its movements. The 70 steering efficiency of the flexible shaft is not lessened when the toy is running on a table on which the flexible shaft lies with a portion of its length, as diagrammatically illustrated in Fig. 8.

When the flexible shaft lies with a portion of its 75 length on the running surface it is possible for the

toy to pass underneath the arch-like curvature 42 of the shaft 27 and perform all kinds of stunts beneath it.

The efficiency and adaptability of the flexible shaft is still further increased when it is fastened or connected to the steering and controlling shaft 23 or to the shaft 37 (Fig. 4) by means of an elastic coupling sleeve 39 (Figs. 7 and 8).

It is also possible to steer and control with the aid of the flexible shaft and the turning movement imparted by it toys which (as is illustrated in Fig. 11) have their front wheels 13 coupled to steering arms 43 connected with each other by means of a transverse member 44. The transverse member 44 is provided with a toothed portion 45 that meshes with a pinion 19, which is actuated by the flexible shaft via the steering and controlling shaft 23, the pinion 22 and the gear 20.

The applicant has distributed the clock-work 20 and the movement transmitting means in the toy 20 and fastened the flexible shaft 27, 40 to the vertically arranged steering and controlling shaft 23 in such a way that the toy body remains suspended in substantially horizontal position with respect to the running surface when the flexible 23 shaft is used as a handle for lifting the toy body from that running surface.

It is further possible to use instead of the flexible shaft 27, 40 a shaft consisting of several separate portions 46 coupled to one another by 30 means of elastic or flexible coupling sleeves, such as the rubber sleeve 47 or the spiral spring 48 illustrated in Fig. 10.

It is further possible to fasten the flexible shaft 21, 40 or 46, 47, 48 directly to the vertical shaft 35 6 of the running and steering wheel 9 as shown in Fig. 6.

When coupling sleeves are used as a coupling means it will always be easy to detach the flexible shaft from the toy body or to replace a 40 short flexible shaft by a longer one or vice versa.

Having thus fully described my invention, what I claim as new and desire to secure by Letters Patent, is:

1. A wheeled toy having the form of an automobile, animal or the like, comprising a body, propelling means mounted therein, driving wheels mounted on said toy body and in driving connection with said propelling means, steering wheels arranged in front of said driving wheels, 60 and a single flexible member of accentuated length for transmitting steering movement to said steering wheels from the outside, said flexible member, having sufficient torsional rigidity to transmit rotational displacement throughout the 65 length thereof without requiring any concentrical supporting members.

2. A toy vehicle, comprising a toy body, propelling means mounted therein, driving wheels mounted on said toy body and in driving connection with said propelling means, steering wheels arranged in front of said driving wheels, and a single flexible member of accentuated length in the form of a flexible spiral for transmitting steering movement to the steering wheels 65 from the outside, said flexible member having sufficient torsional rigidity to transmit rotational displacement throughout the length thereof without requiring any concentrical supporting members.

3. A wheeled toy, comprising a toy body, propelling means mounted therein, driving wheels mounted on said toy body and in driving connection with said propelling means, steering wheels arranged in front of said driving wheels, 75

and a single flexible member of accentuated length in the form of a flexible wire for transmitting steering movement to the steering wheels from the outside, said flexible member having sufficient torsional rigidity to transmit rotational displacement throughout the length thereof without requiring any concentrical supporting members.

4. A wheeled toy, comprising a toy body, a clock-work mounted therein, driving wheels mounted on said toy body and in driving connection with said clock-work, steering wheels arranged in front of said driving wheels, and a single flexible member of accentuated length consisting of a plurality of separate portions joined together by coupling members for transmitting steering movement to the steering wheels from the outside, said flexible member having sufficient torsional rigidity to transmit rotational displacement throughout the length thereof without requiring any concentrical supporting members.

5. A wheeled toy, comprising a toy body, a propelling mechanism mounted therein, driving wheels mounted on said toy body and in driving connection with said propelling mechanism, steering wheels arranged in front of said driving wheels, and a single flexible member of accentuated length connected to the vehicle from above for transmitting steering movement to the steering wheels from the outside, said flexible member having sufficient torsional rigidity to transmit rotational displacement throughout the length thereof without requiring any concentrical supporting members.

6. A wheeled toy, comprising a toy body, propelling means mounted therein, driving wheels mounted on said toy body and in driving connection with said propelling means, steering wheels arranged in front of said driving wheels, a vertically arranged steering shaft for steering said steering wheels and in operating connection with the latter, and a single flexible member of accentuated length connected to said vertically arranged steering shaft for transmitting steering movement to the steering wheels from the outside, said flexible member having sufficient torsional rigidity to transmit rotational displacement throughout the length thereof without requiring any concentrical supporting members.

7. A wheeled toy, comprising a toy body, propelling means mounted therein, driving wheels mounted on said toy body and in driving connection with said propelling means, steering wheels arranged in front of said driving wheels, a vertically arranged steering shaft for steering said steering wheels and in operating connection with the latter, and a detachable single flexible member of accentuated length connected to said vertically arranged steering shaft for transmitting steering movement to the steering wheels from the outside, said flexible member having sufficient torsional rigidity to transmit rotational displacement throughout the length thereof without requiring any concentrical supporting members.

8. A wheeled toy, comprising a toy body, propelling means mounted on said toy body and in driving connection with said propelling means, a running and steering wheel arranged in front of said driving wheels, a vertically arranged steering shaft directly connected to said steering wheel for turning and steering said steering wheel, and a single flexible member of accentuated length connected to said vertically arranged steering

shaft for transmitting steering movement to said running and steering wheel from the outside, said flexible member having sufficient torsional rigidity to transmit rotational displacement throughout the length thereof without requiring any concentrical supporting members.

9. A wheeled toy, comprising a toy body, propelling means mounted therein, driving wheels mounted on said toy body and in driving connection with said propelling means, a running and steering wheel arranged in front of said driving wheels, a steering shaft for steering said steering wheel, gearing in driving connection with said steering shaft and adapted to transmit steering movement from the steering shaft at a reduced ratio, a vertical shaft mounted on said running and steering wheel and in driving connection with said gearing, and a single flexible member of accentuated length for transmitting steering movement from the outside through the steering shaft, ratio reducing gearing and vertical shaft to the running and steering wheel, said flexible member having sufficient torsional rigidity to transmit rotational displacement throughout the length thereof without requiring any concentrical supporting members.

10. A wheeled toy, comprising a toy body, propelling means mounted therein, driving wheels mounted on said toy body and in driving connection with said propelling means, steering wheels arranged in front of said driving wheels, and a single flexible member of accentuated length connected to the toy body about its gravitational center for transmitting steering movement to the steering wheels from the outside, said flexible member having sufficient torsional rigidity to transmit rotational displacement throughout the length thereof without requiring any concentrical supporting members.

11. A wheeled toy, comprising a toy body, propelling means mounted therein, driving wheels mounted on said toy body and in driving connection with said propelling means, steering wheels arranged in front of said driving wheels, and steering means including a single flexible member of accentuated length connected to the toy for transmitting steering movement to the steering wheels from the outside, whereby the direction of the turning movement imparted to the steering means corresponds to the direction of the turning movement of the steering wheels, said flexible member having sufficient torsional rigidity to transmit rotational displacement throughout the length thereof without requiring any concentrical supporting members.

12. A wheeled toy, comprising a toy body, propelling means mounted therein, driving wheels mounted on said toy body and in driving connection with said propelling means, steering wheels arranged in front of said driving wheels, and a single flexible member of accentuated length in the form of a flexible spiral having its coils somewhat spaced apart for transmitting steering movement to the steering wheels from the outside, said flexible member having sufficient torsional rigidity to transmit rotational displacement throughout the length thereof without requiring any concentrical supporting members.

13. A wheeled toy, comprising a toy body, propelling means mounted therein, driving wheels mounted on said toy body and in driving connection with said propelling means, steering wheels arranged in front of said driving wheels, and a single flexible member of accentuated length in the form of a flexible spiral for trans-

- mitting steering movement to the steering wheels from the outside, the individual coils of said spiral being so spaced apart that the distance between the wires of two adjacent coils is smaller than the diameter of the wire of which the spiral is made, said flexible member having sufficient torsional rigidity to transmit rotational displacement throughout the length thereof without requiring any concentrical supporting members.
14. A wheeled toy, comprising a toy body, propelling means mounted therein, driving wheels mounted on said toy body and in driving connection with said propelling means, steering wheels arranged in front of said driving wheels, and a single flexible member of accentuated length in the form of a flexible spiral for transmitting steering movement to the steering wheels from the outside, the diameter of the coils of said spiral being approximately four times the diameter of the wire from which the spiral was wound, said flexible member having sufficient torsional rigidity to transmit rotational displacement throughout the length thereof without requiring any concentrical supporting members.
15. A wheeled toy, comprising a toy body, propelling means mounted therein, driving wheels mounted on said toy body and in driving connection with said propelling means, steering wheels arranged in front of said driving wheels, a steering shaft connected to said steering wheels, a single flexible member of accentuated length for transmitting steering movement to the toy from the outside, and elastic means for coupling said member to said steering shaft of the steering wheels, said flexible member having sufficient torsional rigidity to transmit rotational displacement throughout the length thereof without requiring any concentrical supporting members.
16. A wheeled toy, comprising a toy body, propelling means mounted therein, driving wheels mounted on said toy body and in driving connection with said propelling means, steering wheels arranged in front of said driving wheels, a single flexible member of accentuated length for transmitting steering movement to the steering wheels from the outside, and a handle connected to the outer end of said member, said flexible member having sufficient torsional rigidity to transmit rotational displacement throughout the length thereof without requiring any concentrical supporting members.
17. A wheeled toy, comprising a toy body, propelling means mounted therein, driving wheels mounted on said toy body and in driving connection with said propelling means, steering wheels arranged in front of said driving wheels, a single flexible member of accentuated length for transmitting steering movement to the steering wheels from the outside, and a wheel-shaped steering handle connected to the outer end of said member, said flexible member having sufficient torsional rigidity to transmit rotational displacement throughout the length thereof without requiring any concentrical supporting members.
18. A wheeled toy, comprising a toy body, propelling means mounted therein, driving wheels mounted on said toy body and in driving connection with said propelling means, steering wheels arranged in front of said driving wheels, a single flexible member of great torsional rigidity and free from concentrical supporting elements for transmitting steering movement to the steering wheels from the outside, and a steering mechanism attached to the outer end of said flexible member, said steering mechanism including a steering wheel, and gearing adapted to transmit steering movement from the steering wheel to said flexible member at an increased ratio.
19. A wheeled toy, comprising a toy body, propelling means mounted therein, driving wheels mounted on said toy body and in driving connection with said propelling means, steering wheels arranged in front of said driving wheels, a single flexible member of great torsional rigidity and free from concentrical supporting elements for transmitting steering movement to the steering wheels from the outside, and a steering mechanism attached to the outer end of said flexible member, said steering mechanism including a steering wheel and gearing adapted to transmit movement from the steering wheel to said flexible member at an increased ratio, whereby the direction of rotation of said steering wheel corresponds to the direction of rotation of said movement transmitting means.
20. A wheeled toy, comprising a toy body, propelling means mounted therein, driving wheels mounted on said toy body and in driving connection with said propelling means, steering wheels arranged in front of said driving wheels, a single flexible member of great torsional rigidity and free from concentrical supporting elements for transmitting steering movement to the steering wheels from the outside, and a steering mechanism connected to the outer end of said flexible member, said steering mechanism including a steering wheel provided with an inner tooth, a pinion mounted on a shaft and meshing with said inner tooth, and coupling means mounted on said shaft for coupling said shaft to the outer end of said flexible member.

HEINRICH MÜLLER.
